UNITED STATES PATENT OFFICE.

DANIEL T. McNIEL, OF DETROIT, MICHIGAN.

BELT-PULLEY.

No. 826,185.

Specification of Letters Patent.

Patented July 17, 1906.

Application filed October 5, 1904. Serial No. 227,204.

To all whom it may concern:

Be it known that I, DANIEL T. McNIEL, a citizen of the United States of America, residing at Detroit, county of Wayne, and 5 State of Michigan, have invented certain new and useful Improvements in Belt-Pulleys or the Like, of which the following is a description.

My invention belongs to the general class 10 of pulleys which are adapted to be mounted directly upon a shaft or equivalent part or upon suitable bushings interposed between the shaft and the pulley-hub.

The object is to produce a simple, durable, 15 and effective pulley for the purposes for which such devices are employed.

To this end my invention consists in the novel construction, arrangement, and combination of parts herein shown and described, 20 and more particularly pointed out in the claims.

In the accompanying drawings, wherein like reference characters indicate like or corresponding parts, Figure 1 is a side elevation 25 of my improved pulley with parts broken away to show the construction. Fig. 2 is a diametrical section substantially in line 2 2 of Fig. 1. Fig. 3 is a similar section of a slightly-modified form. Fig. 4 is a partial 30 transverse section of a pulley-rim employed in my invention. Fig. 5 is a similar section of the preferred form of pulley-rim. Figs. 6 and 7 are similar sections showing slight 35 modifications. Fig. 8 is a similar section of the form of pulley-rim shown in Fig. 5 with the pulley arms or spokes secured thereto. Fig. 9 is a partial section of the same on line 9 9 of Fig. 8. Figs. 10 and 11 are partial 40 transverse sections showing the form of rim illustrated in Fig. 7 with slight modifications in the pulley-arms. Fig. 12 is a partial section on line 12 12 of Fig. 11. Fig. 13 is a partial 45 transverse section of a pulley-rim with the arm in place, and Fig. 14 is a partial section on line 14 14 of Fig. 13.

As shown in the drawings, 1 represents the metal rim of a pulley, with its edges flanged inward at an angle to the face, as at 2 2, materially stiffening and strengthening the rim 50 and affording means for connection with the ends 3 of the spokes 4. In the preferred form (shown in Figs. 1, 2, 8, and 9) the margins of the flanges 2 are turned inward, as at 5 5, Fig. 5, and notched, as at 6, for the reception of the ends of the arms 4, which are snugly seated therein, and thus confined

against edgewise movement by the walls 7 7 of the notches, Fig. 6. The outer ends 3 of the arms 4 are formed to suitably seat upon the inner side of the flanges 2 and are secured 60 thereto in any preferred manner. As shown, rivets 8 8 or equivalent means serve to connect the parts. If desired, the extreme end of the arm 4 may be inwardly bent, as at 9, and firmly seated against the under face of 65 the pulley, as shown in Figs. 8, 9, 11, 12, and 13. This construction also serves to strengthen the pulley and tends to relieve the rivets 8 of a part of the strain to which they are naturally subjected. 70

The extent to which the margins 5 of the flanges are employed may be varied as desired. As shown in Fig. 4, such margins and the accompanying notches 6 are dispensed with, the arms being secured to the flanges 75 without other provision for a rigid edgewise connection. As shown in Figs. 2, 3, 8, and 9, the flanges 2 are extended at substantially a right angle to the face of the pulley and the margins 5 turned in at substantially the 80 same angle to the flanges. As shown in Fig. 6, the flanges 2 are extended at an acute angle to the face of the pulley, the notches being formed in the flanges. The arms may be provided with T ends to seat against the 85 flanges. In Figs. 7, 10, 11, and 12 the marginal extensions are folded back upon the flanges, as at 10, thus providing for the retaining-notches 6 and side walls 7. As shown in Figs. 13 and 14, the flanges are slit 90 near the arms, as at 19, and the corners 20 turned over the arms, forming effective means for confining the arm against edge-wise movement and also additional means for binding the arms and flanges together. 95

The hub of the pulley may be of any suitable construction and arrangement and the pulley either solid or separable, as desired. As shown in the drawings, a separable or split pulley is indicated, Figs. 1, 2, 3. As 100 shown, the hub comprises the separable castings 11 11, upon which the outturned ends 12 12 of the arms 4 are seated and secured. Rings 13 13 are positioned upon the ends 12 12 of the arms and the outer end of the hubs 105 and preferably secured thereto by rivets 14 or equivalent means for the purpose. Clamp-bolts 14^a 14^a serve to firmly bind the parts together upon the shaft or upon interposed bushings. Any preferred means may 110 be employed to suitably engage the contiguous ends of the rim-sections. As shown,

lugs 15 15 are secured upon the rim near the intersection thereof, and clamping-bolts 16 serve to firmly bind the lugs, and thus the rim-sections together.

5 In the preferred form the arms for each half of the pulley comprise two parts, each part consisting of the arms for one side or edge of the pulley, which are connected at the hub by an integral web, which, as designated, is the outturned part 12. The arms converge both radially and laterally from the rim toward the hub, Figs. 1 and 2. In the form shown in Fig. 3 the arms for each pulley half are formed from an integral piece of 15 sheet metal, and the two parts or sets of arms for each half are connected by a web 17, the arms being folded back upon the web to form the extension 18 for the rings 13 13.

What I claim as new, and desire to secure 20 by Letters Patent, is—

1. A spoke-pulley provided with a metal rim having at its edges inwardly-disposed flanges bent in two directions and provided with spoke-arms having their outer ends 25 formed to seat upon the flanges and secured thereto.

2. A metal spoke-pulley provided with a metal rim having at its edges inwardly-disposed flanges bent in two directions, and provided with inwardly-converging metal spoke- 30 arms having the outer ends formed to seat upon the flanges and secured thereto.

3. A pulley provided with a metal rim having its edges inwardly flanged with the 35 margins bent inwardly and notched to receive the ends of spoke-arms, in combination with spoke-arms having the outer ends formed to seat upon the flanges, and confined against edgewise movement by the walls of the 40 notches, and means in addition to the flanges for a curing the spoke-arms to the rim.

4. A metal pulley provided with a rim having its edges inwardly flanged with the margins inwardly bent and notched to receive 45 the ends of the spoke-arms, in combination with metal spoke-arms having the outer ends formed to seat upon the flanges and confined against edgewise movement by the walls of the notches, and means in addition to the flanges 50 for securing the spoke-arms to the rim.

5. A metal spoke-pulley provided with a rim having at its edges inwardly-disposed flanges bent in two directions and provided with spoke-arms having the outer ends formed 55 to seat upon the flanges and secured thereto and converging thence both edgewise and sidewise toward the hub of the pulley.

6. A metal pulley provided with a rim having its edges inwardly flanged with the margins inwardly turned and notched to receive 60 the ends of the spoke-arms, in combination with spoke-arms having the outer ends formed to seat upon the flanges and confined against edgewise movement by the walls of the 65 notches, and converging thence toward the

hub of the pulley, and means in addition to the flanges for securing the spoke-arms to the rim.

7. A split pulley comprising sheet-metal rim-sections adapted to form the complete 70 rim, each having the outer edges inwardly flanged and notched, a separable hub, and means for securing the hub on a shaft, in combination with pulley-arms connecting the hub-sections with the rim-sections, the 75 outer ends of the several arms being positioned in the notches, and means in addition to the flanges for securing the spoke-arms to the rim.

8. A split pulley comprising metal rim-sections adapted to form a complete rim and having the outer edges inwardly flanged with the margins inwardly turned and provided with notches to receive the ends of the spoke-arms, a separable hub, and means for securing the hub on a shaft, in combination with spoke-arms connecting the hub-section to the rim-section the outer ends of the several arms being positioned in the notches, and means in addition to the flanges for securing the spoke- 90 arms to the rim.

9. A metal pulley provided with a rim having its edges inwardly flanged with the margins inwardly folded upon the flanges and notched to receive the ends of the spoke-arms, 95 in combination with spoke-arms having the outer ends formed to seat upon the flanges and secured thereto and confined against edgewise movement by the walls of the notches.

10. A split spoke-pulley consisting of substantially duplicate sections, each comprising a semicircular rim with its edges inwardly flanged, and a hub-section, in combination with two convergent sets of arms each set 105 formed independently of the rim and of an integral piece of sheet metal and each arm being secured at one end to one of the flanges of the rim and converging thence both edgewise and sidewise toward the hub-section and secured thereto, and means for securing the hub-sections together.

11. A pulley provided with a sheet-metal rim having flanges at its margins, and spoke-seats formed in said flanges to confine the 115 spoke-arms against edgewise movement, in combination with sheet-metal spoke-arms having their outer ends extended to the margins of the rim and secured to, and seated in the seats formed in, said flanges.

12. A pulley provided with a sheet-metal rim having flanges at its margins, said flanges being notched to receive the ends of the spoke-arms, in combination with sheet-metal spoke-arms having their outer ends positioned in said notches, and means in addition to the flanges for securing the spoke-arms to the rim.

13. A pulley provided with a metal rim having its edges inwardly flanged and 130

- notched to receive the ends of the spoke-arms, in combination with spoke-arms having the outer ends formed to seat upon the inner face of the flanges and offset and also seated against the inner face of the rim, and confined against edgewise movement by the walls of the notches, and means in addition to the flanges for securing the spoke-arms to the rim. 5
14. A metal pulley provided with a rim having its edges inwardly flanged with the margins inwardly bent and notched to receive the ends of the spoke-arms, in combination with metal spoke-arms having the outer ends formed to seat upon the flanges and thence to extend in contact with the inner face of the rim and confined against edgewise movement by the walls of the notches, and means in addition to the flanges for securing the spoke-arms to the rim. 15
15. A split pulley comprising sheet-metal rim-sections adapted to form the complete rim, each having the outer edges inwardly flanged and notched, a separable hub, and means for securing the hub on a shaft, in combination with pulley-arms connecting the hub-section to the rim-section, the outer ends of the several arms being positioned in the notches with the extreme outer ends bent inward and in contact with the inner face of the rim, and means in addition to the flanges for securing the spoke-arms to the rim. 20
16. A pulley having a hub, spoke-arms, and a rim provided with flanges at its edges extending inwardly at substantially right angles relative thereto, the marginal portions of said flanges being inwardly bent and notched for the reception of the outer ends of the spoke-arms. 25
17. A pulley having a hub, spoke-arms, and a rim provided with flanges at its edges extending inwardly at substantially right angles relative thereto, the marginal portions of said flanges being inwardly bent and provided with seats for the reception of the outer ends of the spoke-arms. 30
18. A pulley having a hub, spoke-arms, and a rim provided with flanges at its edges extending inwardly at substantially right angles relative thereto, said spoke-arms being secured at their outer ends to the rim and having straight portions abutting the inner 35
- faces of the flanges and offset ends underlying the rim, and said flanges having inwardly-bent marginal portions provided with seats 55 for said spoke-arms.
19. A pulley having a hub, spoke-arms, and a rim provided with flanges at its edges extending inwardly at substantially right angles relative thereto, said spoke-arms being secured at their outer ends to the rim and having straight portions abutting the inner faces of the flanges and offset ends underlying the rim, and said flanges having inwardly-bent marginal portions notched for the reception of said spoke-arms. 60
20. A pulley having a hub, inwardly-converging sheet-metal spoke-arms arranged with their flat sides facing the sides of the pulley, and a rim provided with flanges at its edges extending inwardly at substantially right angles relative thereto, said spoke-arms being secured at their outer ends to the rim and having straight portions abutting the inner faces of the flanges and ends offset in a direction transversely of the rim underlying the rim. 70
21. A pulley having a hub, inwardly-converging sheet-metal spoke-arms, and a sheet-metal rim having marginal inwardly-extended and notched flanges, the outer ends of said spoke-arms being formed complementary to the notched portions of said flanges and abutting one surface thereof, and rivets securing the flanges and spoke-arms together. 80
22. A split pulley comprising sheet-metal rim-sections adapted to form a complete rim, each having the outer edges inwardly flanged and notched, a separable hub, and means for securing the hub on a shaft, in combination with pulley-arms connecting the hub-section to the rim-section, the outer ends of the several arms being positioned in the notches with the extreme outer ends bent inward and in contact with the inner face of the rim, said arms being secured to the flanges. 90
- In testimony whereof I have hereunto signed my name in the presence of two subscribing witnesses.

DANIEL T. McNIEL.
